US0D1045876S

(12) **United States Design Patent** (10) **Patent No.:** **US D1,045,876 S**
(45) **Date of Patent:** **** Oct. 8, 2024**

(54) **CASE WITH KEYBOARD FOR PORTABLE ELECTRONIC COMPUTING DEVICE**

(71) Applicant: **Pioneer Square Brands, Inc.**, High Point, NC (US)

(72) Inventors: **Brian Lewis Piper**, Seattle, WA (US); **Sudeep Balkrishna Agalgaonkar**, Jamestown, NC (US)

(73) Assignee: **Pioneer Square Brands, Inc.**, High Point, NC (US)

(**) Term: **15 Years**

(21) Appl. No.: **29/948,745**

(22) Filed: **Jun. 22, 2024**

(51) LOC (14) Cl. **14-02**

(52) U.S. Cl.

USPC **D14/440**

(58) **Field of Classification Search**

USPC **D14/440, 447, 250**
CPC ... G06F 1/1628; G06F 1/1626; A47B 23/044; A45C 11/00

(57) **CLAIM**

The ornamental design for a case with keyboard for portable electronic computing device as shown and described.

DESCRIPTION

FIG. 1 is a rear perspective view of case with keyboard for portable electronic computing device showing our new design.

FIG. 2 is a right elevational view thereof.

FIG. 3 is a left elevational view thereof.

FIG. 4 is a top plan view thereof.

FIG. 5 is a bottom plan view thereof.

FIG. 6 is a rear elevational view thereof.

FIG. 7 is a front elevational view thereof; and,

FIG. 8 is a front perspective view thereof.

The broken lines in the drawing figures depict portions of the case with keyboard for portable electronic computing device that form no part of the claimed design.

1 Claim, 8 Drawing Sheets
